UNITED STATES PATENT OFFICE.

JOEL C. WELLS, OF SOUTHBRIDGE, MASSACHUSETTS.

OPHTHALMIC MOUNTING.

1,103,389.

Specification of Letters Patent.

Patented July 14, 1914.

Application filed April 3, 1914. Serial No. 829,242.

To all whom it may concern:

Be it known that I, JOEL C. WELLS, a citizen of the United States, residing at Southbridge, in the county of Worcester and State 5 of Massachusetts, have invented certain new and useful Improvements in Ophthalmic Mountings, of which the following is a specification.

My invention relates to improvements in 10 eyeglasses and has particular reference to finger piece and similar types of glasses.

My invention has for its object the provision of a novel and improved form of coil spring which shall combine the advantageous 15 features of both flat and coil actuating springs and which shall be of maximum efficiency and shall present an attractive appearance.

Figure I represents a fragmentary front 20 view illustrating one embodiment of my invention. Fig. II represents a similar view illustrating another embodiment thereof. Fig. III represents a plan view of Fig. I. Fig. IV represents a plan view of Fig. II. Fig. V represents a sectional view on the line 25 V—V of Fig. III. Fig. VI represents a plan view of one form of my spring such as is employed in Fig. III, and Fig. VII represents a plan view of a spring such as is employed in Fig. IV.

In the drawings, in which similar characters of reference are employed throughout to denote corresponding parts, the numeral 1 designates the bridge having at its end a 30 clip 2 for securing in position the usual lens. Seated in the bridge is a pivot 4 on which 35 swings the lever 5 bearing a nose guard or gripping member 6, these parts being of any usual construction and their particular features forming no part of the present invention.

To actuate the levers and thus force the guards into satisfactory gripping engagement with the nose I employ my improved 45 springs which comprise a helically wound portion 7 substantially circular in cross section inclosed by a wall 8 which is preferably of either flat or but partially round material and is as wide as the length of the helix, as 50 is most clearly illustrated in Fig. V.

In that form of my invention employed in 55 Figs. I and III, I have the terminal portion of the wall 8 resting against the strap or clip 2 to hold this end in position while the other end of the spring extends outwardly and is tied around the lever 5.

In that form of my invention illustrated in Figs. II and IV and which is formed from the blank shown in Fig. VII, I reverse the position of the parts, the portion 7 having an 60 outwardly extending end 9 resting against the strap and projecting across the edge of the portion 8, the coils of the portion 7 being inclosed by the portion 8 which terminates in the end 10 tied around the lever. 65

It is to be noted in both of these forms of my invention the portion 8 serves a double purpose in that it not only forms a part of the spring and by resiliency aids in forcing the levers and guards into correct gripping 70 position, but also on account of its shape it serves to inclose the coils of the spring, particularly when acting in conjunction with the screw head and the lever, so that the coil portion of the spring is protected from dust 75 and dirt which would otherwise tend to clog the spring and also to spoil the appearance of the mounting. It will thus be seen that in my improved spring I attain the efficiency of the usual coil spring with the added efficiency of the flattened portion thereof, while in addition to this the said flattened portion presents an extremely neat and attractive appearance and, as before stated, serves as a dust guard to protect and conceal the otherwise somewhat unsightly coil spring. 85

I claim:

1. An actuating spring for eyeglasses comprising a central helically wound portion and a wide inclosing band.

2. An actuating spring for eyeglasses comprising a central portion of substantially circular shape in cross section and an inclosing spring wall substantially rectangular in cross section.

3. In an eyeglass mounting the combination with a support, a pivot rising therefrom, of a guard lever swinging on the pivot and an actuating spring for the lever comprising a coil wound on the pivot, said 100 spring terminating in a wide portion bent to inclose the coil.

4. An eyeglass mounting including a support for the lenses, a lever mounted upon the support, a pivot for the lever carried by the support, a spring coiled axially with the pivot and terminating in a widened portion inclosing the pivot and portion of the spring coiled directly thereon, said widened portion having its free terminus connected to 110 one of the two first named parts.

5. In an eyeglass mounting the combina-

tion with a support and a headed pivot carried thereby, of a lever mounted on the pivot, a helical spring coiled on the pivot between the lever and head, said helical spring terminating in a wide portion inclosing the helical portion thereof and in engagement with the head and lever, whereby said widened portion forms a protecting wall for

10 preventing access of dirt to the coils of the helix.

In testimony whereof I affix my signature in presence of two witnesses.

JOEL C. WELLS.
